UNITED STATES PATENT OFFICE.

FELIX HOGBERG, OF TACOMA, WASHINGTON, ASSIGNOR OF ONE-HALF TO CHARLES E. HOGBERG, OF TACOMA, WASHINGTON.

BOTTLE CARRIER.

Application filed July 9, 1928. Serial No. 291,201.

This invention relates to devices adapted to be applied to the neck of a bottle, thereby providing a hook or handle whereby the bottle may be safely carried.

5 The objects of my invention are to provide such a device which is of extreme simplicity and which is, therefore, cheap to make; which may be quickly snapped on to a bottle, or removed therefrom; which requires no adjustment or fastening thereto; and which is provided with a surface adapted to receive identification or other marks.

I attain these and other objects by the devices and arrangement illustrated in the accompanying drawings, in which:—

Fig. 1 is a side elevation showing my device as applied to a cream bottle; Fig. 2 is a plan view of the device, removed from the bottle; Fig. 3 is an end elevation thereof; and Fig. 4 20 is a perspective view thereof.

Similar numerals of reference refer to similar parts throughout the several views.

As readily seen in the drawings, my device is of extreme simplicity and comprises a single piece of heavy metal, or other suitable material, bent to the form shown, and of any desired section. The material must be resilient enough to permit it to be sprung on to the neck of the bottle, and stiff enough to 30 clamp itself thereto and for the carrier hook to keep its shape under the weight of the bottle.

The bottle 1 is provided with a flange or enlargement 2, around the upper extremity of 35 its neck 3. My improved carrier is applied to the neck 3 immediately below the said enlargement 2.

My improved carrier comprises the integral bar or wire bent substantially as follows:—The horizontal or base clamping hook 5 is bent to partially encircle the bottle neck 3. This arcuate portion extends from the end 40 6 to the bend 7 and is slightly more than a semicircle in extent, and is of substantially the same diameter, or of less diameter, than the neck 3 of the bottle. The vertical or carrying hook 8 also comprises a substantially 45 arcuate part, extending from the bend 7 of the horizontal hook 5, on a curve to its end 9, which lies in contact with the upper face of

the flange or enlargement 2 of the bottle, thus forming a hook or open loop whereby the bottle may be carried.

The upper surface of the carrying hook 8 may conveniently be flattened, as at 10, to receive any identification marks or advertisements desired.

My device is applied to a bottle by pressing the ends 6 and 7, of the horizontal or clamping hook 5, against the bottle neck 3, below the flange 2, and thereby springing the hook 5 open to cause it to snap on to the said neck. The end 9 of the hook 8 then lies in contact with and immediately above the upper end of the bottle. The entire carrier is therefore firmly clamped in place on the bottle and is ready to be used to carry the bottle.

My improved bottle carrier, therefore, comprises a single piece of stiff, resilient material, such as spring steel or other metal, 70 bent to form two hooks 5 and 8, which lie in planes at right-angles to each other, one of which (5) forms the clamp connecting it to the bottle, and holding the bottle neck firmly in place while it is being carried, and the other of which (8) forms the handle by which the bottle is carried. The hook 8 lies diametrically over the hook 5, as clearly seen in Fig. 2.

Having, therefore, described my invention, 80 what I claim is:—

1. A bottle carrier comprising an integral piece of resilient material, bent to form two hooks, lying in planes at right-angles to each other, the first hook being arcuate and of more than a semicircle between its ends and adapted to snap on to the neck of a bottle, the other hook lying in a vertical plane and extending from and diametrically over said first hook.

2. A bottle carrier comprising an integral piece of resilient and stiff material, bent to form two hooks, lying in planes at right-angles to each other, the first hook being adapted to clamp itself around the bottle neck and the second hook extending upward therefrom and over the end of the bottle to form a handle therefor.

FELIX HOGBERG.
